UNITED STATES PATENT OFFICE.

WILLIAM P. FEENEY, OF HUDSON FALLS, NEW YORK.

AUTOMATIC STUFF-BOX FOR PAPER-MAKING MACHINES.

1,143,523.

Specification of Letters Patent. Patented June 15, 1915.

Application filed May 23, 1914. Serial No. 840,477.

To all whom it may concern:

Be it known that I, WILLIAM P. FEENEY, a citizen of the United States, and a resident of Hudson Falls, in the county of Washington and State of New York, have invented a new and Improved Automatic Stuff-Box for Paper-Making Machines, of which the following is a full, clear, and exact description.

My invention has for its object to provide a stuff box for paper making machines having means to direct back to the chest all surplus stock before the surplus has sufficiently accumulated to increase the pressure at the outlet leading to the mixing box.

Additional objects of the invention will appear in the following specification in which the preferred form of my invention is disclosed.

In the drawings similar reference characters refer to similar parts in all the views in which—

Figure 1 is a side sectional elevation of the invention; Fig. 2 is an enlarged plan view of Fig. 1; Fig. 3 is a transverse sectional view showing the relief valve; Fig. 4 is a transverse sectional view showing the valve leading to the mixing box; and Fig. 5 is a fragmentary sectional view showing pivotal means for the lever with which is connected the relief valve.

By referring to the drawings, it will be seen that a stuff box 10 is provided which is connected with the mixing box 11 by a conduit 12, this mixing box leading to the pump 13 which is provided for forcing the paper stock through the conduit 14 to the screen 15. A head box 16 of the usual construction is provided with a spout 17 leading to the wire 18, mounted in the customary manner. The outlet 19 of the box 10 communicates with the conduit 12 and this outlet 19 may be opened or closed by the valve 20 the sides 21 of which slide in the guideways 22 secured to the end 23 of the said stuff box 10. The stuff box 10 is provided with a partition 24 which extends substantially to the top of the said stuff box and separates the return chamber 25 from the remainder of the stuff box. There is also in the stuff box 10 a partition 26 which extends up from the bottom of the box, but not as far as the partition 24, this partition 26 separating the inlet 27 and the outlet 28 from the outlet 19 which has been described. The stock is pumped into the stuff box 10 through the inlet 27, and after sufficient stock is forced into the box

10 to reach the top of the partition 26, the stock flows over the partition 26 to the outlet 19. It is important that the pressure at the outlet 19 be maintained by the weight of the stock leading to the top of the partition 26. As a means to prevent the stock from accumulating in the box 10, in the partition 26 I provide an outlet 28 with a conduit 29 which is commanded by a relief valve 30. As will be seen by referring to Figs. 1 and 3 of the drawings, the relief valve 30 presses down against the outer end of the conduit 29 which is in the return chamber 25. Secured to this relief valve 30 there is a link 31 which passes through a guide 32 mounted on the partition 24, this link 31 being pivoted at 33 to an arm 34 of a lever 35. Mounted on the lever 35 there is a sleeve 36 which is held in position relatively to the lever 35 by a set screw 37, the sleeve 36 having bearing recesses which are engaged by the pointed screws 38 which mesh in threaded orifices 39 in the arms 40 of the yoke 41, which is secured to the top of the end 42 of the box 10. As a means for adjusting the pressure of the relief valve 30 I mount on the arm 34 of the lever 35, and also on the arm 43 of the said lever, weights 44 which are held in position relatively to the lever 35 by the set screws 45.

Secured for rotating relatively to the valve 20, there is a rod 46 which has a thread 47 meshing in a threaded frame 48 secured to the end 23 of the box 10. The rod 46 may be rotated to raise or lower the valve 20 by means of the hand wheel 49.

It will be understood that in using the invention, the weights 44 may be adjusted on the arms 34 and 43 of the lever 35, so that the desired pressure may be obtained at the outer end of the conduit 29 by the relief valve 30. Should the paper stock accumulate in the box 10 in sufficient quantities to reach a point any predetermined height above the partition 26, with the adjustment of the weights 44, the relief valve 30 will be automatically opened to permit the escape of the paper stock so that the said paper stock may flow into the return chamber 25 and from the return chamber to the conduit 50 which leads to the chest.

Having thus described my invention I claim as new and desire to secure by Letters Patent:

1. In a device of the character described, a mixing box, a stuff box having an outlet

to the mixing box and an inlet, a second outlet for the stuff box with its outer end extending upwardly, and a relief valve at the outer end of the second mentioned outlet.

- 5 2. In a device of the class described, a mixing box, a stuff box having a partition and an inlet for the stuff box at one side of the partition, an outlet for the box at the other side of the partition and leading to the
10 mixing box, an outlet conduit at the first mentioned side of the partition and extending upwardly, a relief valve at the outer end

of the outlet conduit, a pivoted lever, a link connecting an arm of the lever with the relief valve, and means for adjusting the balance of the lever.

In testimony whereof I have signed my name to this specification in the presence of the two subscribing witnesses.

WILLIAM P. FEENEY.
